UNITED STATES PATENT OFFICE.

D. MAURICE HARTSOUGH, OF MINNEAPOLIS, MINNESOTA.

STARTER FOR EXPLOSIVE-ENGINES.

1,105,775.

Specification of Letters Patent.

Patented Aug. 4, 1914.

Application filed May 18, 1912. Serial No. 698,191.

To all whom it may concern:

Be it known that I, D. MAURICE HARTSOUGH, a citizen of the United States, residing at Minneapolis, in the county of Hennepin and State of Minnesota, have invented 5 certain new and useful Improvements in Starters for Explosive-Engines; and I do hereby declare the following to be a full, clear, and exact description of the invention, such as will enable others skilled in the art to which it appertains to make and use the same.

My invention relates to explosive or internal combustion engines, and has for its 15 especial object the provision of an improved engine starter.

Generally stated, the invention consists of the novel devices and combinations of devices hereinafter described and defined in 20 the claims.

In accordance with my invention, I utilize a portion of the gas compressed in one or more of the engine cylinders, as a medium for starting the engine. Under the control 25 of mechanism hereinafter described, I store this gas in a reservoir and introduce the same into the engine cylinder or cylinders to start the engine. As an additional feature of novelty, I also utilize the gas, thus stored 30 for illuminating purposes, suitable gas lamps or burners and gas conducting conduits being provided for that purpose.

The invention, while capable of general application in connection with explosive or 35 internal combustion engines, nevertheless, is especially adapted for application to automobiles, and in such applications thereof, those devices which are used to control, at will, the supply of the charge into the storage reservoir and the charging of the engine, by the use of the charge thus stored, are 40 preferably extended to the front or foot board where they will be within easy reach of the chauffeur or operator of the machine. 45 Also, in such application, the stored gas may be utilized to supply the head light and other lamps of the machine.

The invention also involves very important and novel features of construction and 50 arrangement of parts whereby the above noted objects or results are accomplished in an extremely simple, efficient and satisfactory manner, all of which features are illustrated in the accompanying drawings, 55 wherein like characters indicate like parts throughout the several views.

Referring to the drawings, Figure 1 is a

view in side elevation with some parts broken away and some parts sectioned, showing my invention applied to the multi-cylinder explosive engine of an automobile; Fig. 2 is an end elevation of the engine, some parts being sectioned and some parts being removed; Fig. 3 is a detail in section taken approximately on the line $x^3 x^3$ on 60 Fig. 1; Fig. 4 is a detail in front elevation, showing the so-called starting valve controller; and Fig. 5 is a section taken approximately on the line $x^5 x^5$ on Fig. 4.

The invention is adapted for application 70 either to the single cylinder or multi-cylinder explosive engines, either of the two-cycle or four-cycle type, but it involves certain highly important features which also especially adapt it for application to multi-cylinder engines.

The engine illustrated in the drawings will be assumed to be a four-cylinder explosive engine of the four-cycle type, and of the parts thereof, it is only desirable for the 80 purpose of this case to note the cylinders 1, the crank shaft casing 2, and the crank shaft 3, which parts may be of the usual or any suitable construction.

The numeral 4 indicates the front or foot 85 board of an automobile.

In the application of my invention, I employ a suitable gas storage tank 5 which will be suitably supported, preferably, under the body of the automobile. This storage tank 90 5 is connected by a so-called charging pipe 6 to a port 7^a in one side of one of the cylinders 1. The port 7^a may be differently located, according to the pressure which it is desired to maintain in the storage tank 5, 95 but for the purposes of this case, we will assume that it is located at a point where, just before it is closed by an upward or inward movement of the piston 1^a , the compression will have reached thirty pounds. 100 Interposed in the charging pipe 6 is a normally closed so-called charging valve 7 and a valve casing 8. The arm 9 of the charging valve 7, is shown as connected to the front end of a rod 10, the rear end of which is extended through the front board 1 of the automobile and terminates in a knob 11, which is within reach of the operator or driver. Working within the valve casing 8 is an automatically driven and properly timed 105 rotary cut-off valve 12, that intermittently opens and closes the charging pipe 6, as will more fully appear in the description of the operation. This valve may be driven in 110

different ways from the engine crank shaft, but, as shown, its shaft projects at one end and is provided with a spur gear 13 that meshes with a spur gear 14 secured to short shaft 15 journaled in one end plate of the crank shaft casing 2. Within the casing, the shaft 15 is provided with a spur gear 16 that meshes with an intermediate gear 17 on the said casing. The intermediate gear 17 meshes with a pinion 18 on the crank shaft 3. The pinion 18 is one-half the diameter of the gear 16, so that the shaft 15 is given one rotation for each two rotations of the crank shaft. The gears 13 and 14 are of the same diameter, and hence, the cut-off valve 12 will also be given one rotation for each two rotations of the engine crank shaft.

The upper end of each cylinder 1 is connected to the storage tank 5, and this may be done in different ways, but, as shown, it is accomplished by a so-called starting pipe 19 which, for convenience, taps the lower portion of the charging pipe 6 and is provided with branches 20 that open into the upper portions of the respective cylinders. In each branch pipe 20 is a normally closed valve 21 having arms 22, each connected to one end of an individual operating rod 23. The other ends of the operating rods 23 are brought forward, and, as an important feature of this invention, are connected to individual bearings 24 that are circumferentially spaced and connected preferably, to a laterally flexible metal ring 25. The ring 25 may be supported in different ways, but, as shown, this is accomplished by passing the rear ends of the rods 23 through guide passages 26 formed in the front board 4. As there are four cylinders, and hence four operating rods 23, the rod branches 24 are equi-distantly spaced on quadrants of the flexible ring 25 to which they are attached.

Located at the axis of the bearing ring 25 and mounted for rotary and limited end-wise movements in bearings 27 and 28, respectively, on the rear cylinder 1 and in the front board 4, is a shaft 28, shown as provided with a sprocket 29 that alines with the sprocket 30 secured to the gear 14, or otherwise connected for rotation therewith. The sprockets 29 and 30 are of the same size, and a sprocket chain 31 runs over the same, so that the shaft 28 will be driven at the same rate as the intermediately acting cut-off valve 12, that is, will be given one rotation for each two rotations of the engine crank shaft, this being, assumed, a four-cycle engine. Rigidly secured to the outer or rear end of the shaft 28 is a so-called selecting arm 32, preferably provided at its free end with a roller 33, is adapted to engage and run over or against the flexible ring 25. The so-called selecting arm 32 is so positioned in respect to the direction of

its rotation and is so timed in respect to the engine crank shaft, that it will aline, in succession, with the bearings 24 of the valve actuated rods 23, and will be alined with any particular one thereof, at a time when the piston of the corresponding cylinder has just commenced its outward or downward movement of an explosion stroke, or stroke corresponding in time to the explosion stroke. The purpose of this will more fully appear in the description of the operation.

The rearward movement of the shaft 28 is limited by a stop collar 34 thereon, which engages the bearing 27, and it is yieldingly pressed rearward by a coiled spring 35, shown as compressed between said bearing 27 and the hub of the arm 32. As shown, an operating knob 36 is swiveled to the extreme rear end of the shaft 28. Coiled springs 23^a, as shown, are connected to the rods 23 and to the front board 4, independently operate to press the said rods rearward and to hold the corresponding starting valves 21, normally in closed positions.

In Fig. 1, the numeral 37 indicates a head, light or other lamp of the automobile, the same, as shown, being connected to the storage tank 5 by a pipe 38 which taps the charging pipe 6. In the pipe 38 is a reduction valve 39. The charging pipe 6 is provided with a check valve 40 which permits a flow of gas under pressure from the engine cylinder into the storage tank 5, but checks a reverse flow. The starting pipe 19 is shown as provided with two check valves 41 and 42, which operate in the same direction and both of which permit the flow of gas from the storage tank into the engine cylinders, but check a reverse flow. The two check valves are provided only for additional safety against back-firing from the cylinders into the storage tank. The numeral 43 indicates a pressure gage shown as located on the front board 4 and connected to the storage tank 5 by a small pipe 44.

Operation: The operation is substantially as follows: When there is no pressure in the storage tank or when the pressure therein is too low, to-wit, lower than the assumed desirable pressure of thirty pounds per square inch, the pumping mechanism is thrown into action by the operator who simply pulls on the stop 11 and thereby opens the charging valve 9. When this is done, the rear cylinder and piston in the construction illustrated, will be rendered operative as a pump to force the compressed gas into the storage tank. The manner in which this charging is further controlled is, as follows: The cut-off valve 12 is so timed that it will open the charging pipe 6 for a short interval of time during the compression stroke of the rear piston and while the said piston is moving approxi-

mately from a position in which the pressure has reached thirty pounds, and during this interval, if the charging valve 9 be open, as stated, gas will be forced from the rear 5 cylinder into the charging tank, providing the pressure of the said charging tank is lower than thirty pounds. Gas will not be forced into the said tank from the said cylinder after the pressure therein on the compression stroke exceeds thirty pounds, because, at that time, the piston will have 10 closed the port 7. At all other times except during the short interval just noted, the cut-off valve 12 closes the charging pipe 6; 15 so that there is no communication between the cylinder and the charging tank at any time during the explosion stroke or during the exhaust stroke, or admission stroke. Hence, the obvious importance of the said 20 cut-off valve timed to run automatically, as stated. The check valve 40 prevents back surging of the gas from the storage tank into the cylinder during a short interval of time while the valve 12 opens the charging 25 pipe and during a part of which time the pressure within the cylinder, while above twenty pounds, will be less than thirty, and when, at certain times, the pressure in the tank 5 may be less than thirty-pounds, but 30 more than twenty pounds. The charge of the gas must, of course, take place while the engine is in action. The operator, when noting on the indicator 43 that the pressure in the storage 7 is considerably below thirty 35 pounds, starts the pumping action and recharges the reservoir, as above stated.

Gas for lighting purposes is, as is evident, always available. The reduction valve 39 must, of course, be of the character which 40 will properly reduce the high pressure gas to a pressure proper for burning. The tank or burner may be of any suitable character, and, if necessary, any suitable auxiliary device may be employed for supplying additional air to the gas at the burner or at any 45 other suitable point.

No matter in what position the engine crank shaft stops, the piston of one or the other of the cylinders will be at some part of 50 its working stroke, so that the introduction of gas, under pressure into that cylinder, will have the effect of starting the engine, and furthermore, the so-called selecting arm 32 will be in position where, if pressed forward, it will operate on the corresponding 55 rod 32 through the flexible ring 25 and will open the starting valve 21 of that cylinder. If, when this is done, the piston referred to was at the beginning of its working or explosion stroke, the initial charge into the 60 first cylinder will usually be sufficient to start the engine. But at any rate, it will be sufficient to impart an initial movement to the engine crank shaft, which will, if the 65 arm 32 be still pressed rearward, immediately

cause the gas under pressure from the tank 5, to be introduced into the next cylinder, the piston of which is just beginning its working or explosion stroke. In this way, simply by pressing rearward on the knob 70 36, the engine is started into action by introduction of the gas under pressure into the proper cylinders in the proper order of succession and at exactly the right times to start the engine by a multiplicity of successive pressure impulses. Furthermore, the gas, thus introduced into the cylinders for the purpose of imparting initial movement to the crank shaft and instantly rendered 75 available as the explosive medium, and thus the engine will be started and its action may be continued by the explosions which follow, and while relying upon the carbureter's supply and charges for the initial explosions. This, as is evident, makes it unnecessary to 80 prime the cylinders by the introduction of gasoline, as has frequently been necessary under certain conditions of the atmosphere. As is obvious, there will be no harm done even if the arm 32 be held in action longer 85 than necessary. As the several springs 36 will automatically close the starting valves 23 in the proper order of succession, the roller 33 of the said arm 32 passes out of 90 action on the rods 23. This positively insures a good starting action, requires no skill on the part of the operator. Otherwise stated, the device is what is frequently designated as "fool proof." The selection of the proper cylinder in the control of the introduction of the initial charges of gas into the cylinders is automatically taken care of by the timing of the so-called selecting arm 32 in respect to the crank shaft and pistons. 95

What I claim is:

1. The combination with a multi-cylinder explosive engine, of a storage reservoir adapted to contain an elastic fluid under pressure, conduits connecting the engine cylinders to said reservoir, normally closed starting valves in said conduits, and valve actuating connections including a rotary selector driven from said engine with a properly timed action, and valve actuating rods grouped about said selector and arranged to 100 be successively acted upon by said selector, when the latter is rendered operative, and to thereby progressively open said starting valves in the proper order of succession. 105

2. The combination with a multi-cylinder explosive engine, of a storage reservoir adapted to contain an elastic fluid under pressure, conduits connecting the cylinder of said engine to said reservoir, normally closed starting valves in said conduits, valve actuating connections comprising a selector rotated from the engine and having a lateral movement, and valve actuating rods independently connected to said starting valves and having circumferentially spaced por- 110 115 120 125 130

- tions adapted to be operated upon in succession, by said selector, when the latter is moved laterally, and to thereby progressively open said starting valves in the proper order of succession.
3. The combination with a multi-cylinder explosive engine, of a storage reservoir for containing an elastic fluid under pressure, conduits connecting the engine cylinder to 10 said reservoir, normally closed starting valves in said conduits, a flexible ring, rods independently connecting said starting valves to said ring, and a selector driven from said engine, with a properly timed action, over the face of said ring and movable into action on said ring, to progressively open said starting valves.
4. The combination with an explosive engine of the four-cycle type, of a storage reservoir, charging and starting conduits connecting said reservoir, respectively, to the intermediate portion of one side and to the compression end of the cylinder of said engine, a valve in said charging conduit for 20 controlling the transfer of compressed gas from the engine cylinder into said storage tank, and a valve in said charging conduit for controlling the supply of gas from said tank to the engine cylinder for starting the engine.
5. The combination with an explosive engine of the four-cycle type, of a storage reservoir, charging and starting conduits connecting said reservoir, respectively, to the intermediate portions of one side and to the compression end of the cylinder of said engine, a valve in said charging conduit for 30 controlling the transfer of compressed gas from the engine cylinder into said storage tank, a valve in said charging conduit for controlling the supply of gas from said tank to the engine cylinder for starting the engine, and check valves in said charging and starting conduits.
45. 6. The combination with an explosive engine of the four-cycle type, of a storage reservoir, charging conduits and starting conduits connecting said reservoir, respectively, to the intermediate portion of one side and 50 to the compression end of the cylinder of said engine, a normally closed charging valve in said charging conduit, a rotary cut-off valve, means for driving said rotary cut-off valve from the engine crank shaft with a properly timed action, for opening the same during the compression stroke, and a normally closed starting valve in said starting conduit.
7. The combination with an explosive engine of the four-cycle type, of a storage reservoir, charging conduits and starting conduits connecting said reservoir, respectively, to the intermediate portion of one side and 60 to the compression end of the cylinder of said engine, a normally closed charging valve in said charging conduit, a rotary cut-off valve, means for driving said rotary cut-off valve from the engine crank shaft with a properly timed action, for opening the same during the compression stroke, and a normally closed starting valve in said starting conduit.
- and to the compression end of the cylinder of said engine, a normally closed charging valve in said charging conduit, a rotary cut-off valve, means for driving said rotary cut-off valve from the engine crank shaft with a properly timed action, for opening the same during the compression stroke, a normally closed starting valve in said starting conduit, and check valves in said charging and starting conduits.
8. The combination with a multi-cylinder engine, of a storage reservoir, charging conduits and a starting conduit in communication with said storage tank, said charging conduit communicating with one engine cylinder through the intermediate portion of one side wall thereof, said starting conduit 75 having branches leading to the compression ends of the several cylinders, normally closed starting valves in the several branches of said starting conduits, and a selector driven from the engine with a properly timed action and progressively operative to open said starting valves in succession when thrown into action.
9. The combination with a multi-cylinder engine, of a storage reservoir, charging conduits and a starting conduit in communication with said storage tank, said charging conduit communicating with one engine cylinder through the intermediate portion of one side wall thereof, said starting conduit 85 having branches leading to the compression ends of the several cylinders, normally closed starting valves in the several branches of said starting conduits, and a selector driven from the engine with a properly timed action and progressively operative to open said starting valves in succession when thrown into action.
10. The combination with a multi-cylinder engine, of a storage reservoir, charging conduits and a starting conduit in communication with said storage tank, said charging conduit communicating with one engine cylinder through the intermediate portion of one side wall thereof, said starting conduit 90 having branches leading to the compression ends of the several cylinders, normally closed starting valves in the several branches of said starting conduits, and a cut-off valve in said charging conduit driven from the engine with a properly timed action for opening said conduits.
11. The combination with a multi-cylinder engine, of a storage reservoir, charging conduits and a starting conduit in communication with said storage tank, said charging conduit communicating with one engine cylinder through the intermediate portion of one side wall thereof, said starting conduit 95 having branches leading to the compression ends of the several cylinders, normally closed starting valves in the several branches of said starting conduits, and a selector driven from the engine with a properly timed action and progressively operative to open said starting valves in succession when thrown into action, and a cut-off valve in said charging conduit driven from the engine with a properly timed action for opening said conduits.
12. In testimony whereof I affix my signature in presence of two witnesses.
